UNITED STATES PATENT OFFICE.

EDWARD A. RIX, OF SAN FRANCISCO, CALIFORNIA.

AIR-COMPRESSOR.

1,182,507.

Specification of Letters Patent.

Patented May 9, 1916.

Application filed June 25, 1914. Serial No. 847,208.

To all whom it may concern:

Be it known that I, EDWARD A. RIX, a citizen of the United States, residing at the city and county of San Francisco and State of California, have invented new and useful Improvements in Air-Compressors, of which the following is a specification.

This invention relates to a multi-cylinder air compressor, and pertains especially to a cylinder arrangement therefor and a single rotary valve to control inhaust and exhaust.

One of the objects of the present invention is to provide a simple, substantial, multi-cylinder, high-speed compressor in which the cylinders are radially arranged in such fashion that, together with a novel form of rotary valve mechanism, a relatively long valve travel may be secured for a small motion of the piston, thus allowing the ports to be large and to remain wide open a relatively long period of time.

Another object of the invention is to reduce the clearance between the cylinders and valve to leave the smallest space possible, and to correspondingly reduce the area or diameter of the valve.

Further objects will hereinafter appear.

The invention consists of the parts and the construction and combination of parts as hereinafter more fully described and claimed, having reference to the accompanying drawings, in which—

Figure 1 is a vertical cross section of the compressor. Fig. 2 is a front view of the compressor, showing the rotary valve removed. Fig. 3 is a cross section of the valve on the line 3—3, Fig. 1.

Referring to the drawings, A indicates a plurality of radially disposed cylinders, 40 which are secured, as at 2, to a face-plate 3, formed integral with a base casting or standard 4.

6 is a shaft journaled in a bearing formed on the upper end of the standard 4 and extending through the center portion of the multi-cylinder casting.

7 is an eccentric formed integral with the shaft, or otherwise secured to same, and which is positioned between the multi-cylin-

der unit and the plate 3. Surrounding the eccentric is a segmental ring 8, of suitable construction, and connecting said strap with pistons 9 is a series of connecting-rods 10; connection being formed between each piston and rod by any convenient means, as an angularly projecting pin or stud 11, which extends through a slot 12 formed in the side of each cylinder.

Formed integral with the multi-cylinder casting in a central position on same is an extension 13, in which is formed a valve chamber, and connecting said chamber with the inner end of each individual cylinder is a port 14. A rotary disk-shaped valve 15 is suitably secured on the outer end of shaft 6, 65 which latter projects into the valve chamber; valve 15 being provided with two ports 16 and 17, one of which 16 being the inlet and 17 the outlet. Port 16 is formed on the inner face of the valve 15 and is adapted to 70 communicate with a central passage 18 formed in the center of the cylinder casting and is also adapted to communicate with the ports 14; the central passage 18 being open to the atmosphere by means of a plurality 75 of radially disposed ports 19 arranged substantially as shown in Figs. 1 and 2. Port 17, or the exhaust port, extends clear through the valve and is adapted to form an outlet for the compressed air from a cylinder and 80 port 14 into the valve chamber, from where the air may be conducted through a pipe or similar means connected with an extension 20, the valve chamber being closed by a suitable means, as a plug 21. 85

In operation, power is transmitted through shaft 6, preferably by making a direct connection with an electric motor or the like. The rotary movement of the shaft will thus be transmitted through the eccentric 7, straps 8 and connecting rods 10 to the pistons 9 which will consequently be reciprocated within the cylinders A. Valve 15 being secured on the outer end of the shaft will correspondingly turn with the shaft, in conjunction with the reciprocating pistons, in such a manner as to present the inlet port 16 in the right position, with relation to an out-

wardly moving piston, and exhaust port 17 in position with a cylinder under compression. The outward movement of the piston within the cylinder will cause a suction in the usual manner and cause the air to be drawn from the outside atmosphere through the ports 19, central passage 18, and ports 16 and 14 into a cylinder. The continuous revolving movement of the shaft will bring the port 16 out of register with the port 14 the moment piston 9 begins to travel inwardly for compression, and will similarly bring the port 17 into register with said port 14 until the piston 9 has completed the compression stroke.

The inner ends of the cylinders, together with the pistons mounted therein, are preferably conoidal, as shown in Fig. 1. This permits the cylinders to be placed very close together and consequently permits reduction of the valve area to a minimum. The close relation between the inner abutting ends of the several cylinders permits a close arrangement of the ports 14 and consequently the application of a valve of small diameter. A small valve thus produced consumes very little power for its operation and is, furthermore, automatically seated by the pressure of the exhausting air in the valve chamber. The arrangement of the ports 16 and 17, furthermore, permits a relatively long valve travel for a small motion of the piston, thus allowing the ports to be large and to remain wide open a good portion of the piston stroke.

The driving connection formed between the shaft and pistons permits a high speed of operation, and the driving connection between the shaft and valve, together with the arrangement of the ports, permits the use of a single automatically operated valve, both for exhaust and inlet, in conjunction with a plurality of cylinders.

While the cylinders and pistons here shown are conical shape at their inner ends for the purpose of producing the smallest diameter of valve and the least loss possible, with relation to clearance, it is obvious that these may be entirely eliminated in larger units. It should also be understood that the air may be admitted in any suitable or convenient manner.

This is essentially a high speed compressor, and in order to make it efficient at a high speed a mechanical valve must be used, and preferably a rotative valve of the character shown, which gives a relatively long valve travel for a small motion of the piston, thus allowing the ports to be large and to remain wide open a good portion of the time. This permits very high rotative speed otherwise unattainable with any economy. Inasmuch as the discharge pressure holds the valve on its seat, it is evident

that the minimum power expended in driving the valve will be when the valve is of the smallest possible diameter. In order to make this diameter within the necessary limits, it is necessary to butt the working ends of the cylinders at the center. The working ends of the cylinders cannot be placed on their outward ends, for a port leading from these outward ends to a valve at the center would have such an amount of clearance that at a very small pressure the clearance would absorb the entire contents of the cylinder and no work could be done. Three requisites, therefore, are combined in this invention, namely: small diameter of rotative valve; short clearance; and centrally abutting cylinders. I have shown the cylinders covered with radiator fins for air cooling. The machine can be made either air or water cooled, as desired.

It is manifest that various changes in form, proportions and minor details of construction may be resorted to within the scope of the appended claims and I do not wish to limit myself to the specific design and construction here shown.

Having thus described my invention, what I claim and desire to secure by Letters Patent is—

1. In a compressor of the class described, the combination of a plurality of radially arranged cylinders, each having a single port at its inner end, a rotatable ported valve, the ports of said valve being so disposed that each port will register with the single port of the cylinders upon rotation of said valve to control the inlet and outlet for each cylinder in succession.

2. In a device of the class described, the combination with a plurality of radially disposed cylinders having conoidal inner ends, to permit the same to be assembled in close correlative relation one with the other, of a central valve chamber, said cylinders each having a single port connecting said conoidal cylinders with the valve chamber, and a rotatable valve having ports so disposed that they will each register with the port of said cylinders.

3. In a compressor of the class described, the combination of a plurality of radially disposed abutting cylinders each having a conoidal inner end provided with a single port, a rotatable valve adjacent to the abutting ends of the cylinders, radially disposed ports between the cylinders in communication with the atmosphere and adapted to supply air to one side of the valve, said valve having ports adapted to register with the single port of each cylinder to control intake and exhaust of said cylinders.

4. In an air compressor, a plurality of radially disposed cylinders having a series of concentrically disposed ports, and an inlet

chamber concentrically disposed within the line of said ports, radial inlets leading to said chamber, a shaft extending through said inlet chamber, a valve chamber having an exhaust opening and a rotatable valve on said shaft within said valve chamber connecting the cylinders periodically with the air inlet chamber and the exhaust opening.

In testimony whereof I have hereunto set my hand in the presence of two subscribing 13 witnesses.

EDWARD A. RIX.
